CLAIM

The ornamental design for a package for absorbent articles, as shown and described.

DESCRIPTION

FIG. 1 is a front perspective view of a package for absorbent articles, embodying the new design;

FIG. 2 is a front view of the design shown in FIG. 1;

FIG. 3 is a back view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in the drawings depict environmental structure and form no part of the claimed design. The claim comprises only the solid lines shown in the figures.

1 Claim, 3 Drawing Sheets
